EDWARD F. LINTON, OF EAST NEW YORK, N. Y.

IMPROVEMENT IN PYROTECHNIC SIGNALS.

Specification forming part of Letters Patent No. 175,359, dated March 28, 1876; application filed February 14, 1876.

To all whom it may concern:

Be it known that I, EDWARD F. LINTON, of East New York, in the county of Kings and State of New York, have invented a new and useful Improvement in Pyrotechnic Night-Signals; and I do hereby declare that the following is a full, clear, and exact description thereof, reference being had to the accompanying drawings, forming a part of this specification, in which—

Figure 1 is a front elevation of the signal. Fig. 2 is a vertical sectional view of the same. Figs. 3, 4, and 5 represent different views of the stars.

The present invention is an improvement in the class of signals known as pyrotechnic night-signals, and is designed to be used, as such, in connection with any public or private system or code in which different colors or combination of colors are employed to represent numerals or letters, and whereby said characters thus represented are rendered the media of intelligent communication. In the day-time any information which the code or system of signals is susceptible of imparting can readily be spoken or conveyed, as is well known, by means of flags, &c., the color or colors of which being different, and each representing a certain numeral or other character. When either of the flags representing the code is displayed, or any series of them in succession, the information they are thus caused to speak or convey is intelligible, and readily understood by all who have a key, or are familiar with the system or code in connection with which they are used. At night, or when it is dark, as a means of signaling, flags and all kindred devices are, of course, valueless, and, consequently, as a substitute for night-signaling, colored lights or pyrotechnic signals, exhibiting different colors or combination of colors, said colors corresponding with those of the day-signals, have for a long period been used.

But, as fully attested by practical experience, the class of signals now in general use, and known and recognized as pyrotechnical night-signals, are not only, for many reasons, most objectionable, but, on some occasions, are entirely inadequate to accomplish results which are most important, and much desired. In

the first place, the pyrotechnic night-signals now in general use are what may be termed "stationary signals"—that is, they do not project or throw to an altitude or distance the composition through the burning of which their brilliancy is exhibited, and their color rendered discernible, and, as a consequence, the signal being held in the hand, and being composed of compositions that in burning throw off a kind of lava, the same frequently falls on the hands, inflicting a serious burn. Besides, being a fixed light of powerful illuminating properties, when burned on the deck of a vessel the illumination caused would cause the signal to disclose surrounding objects in a manner sometimes most objectionable—for instance, in time of war the brilliancy of the light being such as to fully disclose the character of the vessel from which the signal is fired; and again, the fixed character of the ordinary night-signal renders it difficult, and sometimes impossible, to convey intelligence to a fleet in rough weather, with a high sea running; and again, the fixed character of the signal renders it altogether inadequate to convey any intelligence where one vessel is separated from another by any point of land, or other natural or artificial obstruction—as, for instance, when one vessel is inside and the other outside of a harbor; and again, the ordinary night-signal being composed of a slow-burning composition much valuable time is lost when it is desired to signal rapidly, and much valuable time is also lost when it is necessary to signal from a flag-ship to each vessel of the fleet. Especially is this the case when the flag-ship is in the center, and is surrounded by the other vessels of the fleet, as signals under such circumstances have to be exhibited forward and aft, and also at the sides of the ship, to insure of their being seen and recognized by the entire fleet. And another most serious and important objection to the ordinary signal is that, owing to the nature of its composition, it is very difficult to protect the same from deterioration through atmospheric influences.

Now, the object of the present invention is to produce a pyrotechnic night-signal equally as, if not more, brilliant than the signals now in general use, and one which is entirely free

from each and every one of the series of objections hereinbefore enumerated.

In my improvement the colored signal balls or stars being projected far into the air, no lava is formed which can possibly fall and burn the hand. They do not illuminate surrounding objects, or the vessel from whose deck they are fired, and the signal balls or stars being thrown several hundred feet into the air permits of the signal being used successfully in a heavy sea, or where land or other objects intervene between vessels or parties employing the signals as media of communication. Their rapid discharge, and the altitude at which their brilliancy is displayed, obviate the necessity of burning more than one for each subject of communication; and, finally, the construction of my signal is such as to secure absolute protection from atmospheric action or chemical change.

In constructing my signal I utilize the well-known principle of the "Roman candle," and the nature of my invention is found in connection with certain essential and most important improvements, in connection with the construction of the "stars," the "time-fuses," the "powder-chambers," the means of ignition, &c., all as hereinafter described.

To enable others skilled in the art to make and use my invention, I will now proceed to describe its construction and method of operation.

In the accompanying drawing, A is the case, and is of cylindrical form, and may be constructed of any suitable material. The relative proportions illustrated in the accompanying drawing, where the case is about eight inches in length, one and a half inch in diameter, leaving a vertical annular chamber, say, of an inch and a sixteenth in diameter, is well suited for a signal that is designed to contain three colored stars, but there is nothing arbitrary about these dimensions, as they may be changed at pleasure, without in any manner affecting the principle of my improvement. B is the plug of clay, or other non-combustible material, and is rammed or packed in the case in the usual manner. C¹ C² C³ are time fuses, and may be constructed of any of the compositions known to pyrotechnic chemistry, as suited for the purpose designed. The lower and upper time-fuses C¹ and C² may be of any desired depth, provided the lower one is of depth sufficient to contain the powder-chamber c, and the depth of the upper one, C³, is sufficient to provide such a quantity of the composition as will insure the ignition of the powder in the chamber c². The dimensions or quantity of the composition, which the intermediate time-fuses C¹ and C² shall contain must be such as to insure of their burning without igniting the powder in the chamber below during such an interval as will be consumed by the projected star in burning, and until its entire extinguishment occurs, and then cause the ignition of the powder in the chamber below. D D are the

colored stars, and they are to be constructed of such compositions as will cause the different signals to represent such colors, or combinations of colors, as will fully meet the exigencies of the code or system in connection with which they are to be used. What exactly these colors or combinations of colors shall be, the code itself will determine. Consequently, this is no part of my invention; nor is it necessary to give a formula that will recite the ingredients necessary to produce stars representing different colors, or combinations of colors, as from the earliest stages of the art, all who are familiar with chemistry as applied to pyrotechny, have known of these compositions.

But in constructing stars for night-signals, I have discovered that it is necessary they should be exceedingly strong, and so constructed, as, if possible, to do away with all danger of their breaking, or the composition becoming disintegrated. Therefore I do away with the vertical annular channel for the quick match, which, in the stars of the Roman candle, is invariably at the center, and which, being used for the purpose of ignition, necessarily must extend through the entire surface of the star, and which weakens the same at the point where the greatest force of the powder is expended or exerted; and form the channels of ignition, or for the quick match, by providing one or more vertical grooves at the lateral face or faces of the star. In Fig. 3 a star is shown having four of such grooves, as seen at d d. Yet notwithstanding the disadvantage for the reason stated and others hereinafter mentioned, and which result from having the stars formed with a channel through their center, there are certain demands which the central channel of the stars of the Roman candle meets, which, for the purposes of pyrotechnic night-signaling, are most important—that is, it lights the star within the body of the composition, and in and around the center thereof, which affords a most sure guarantee that the star will not be blown out in consequence of its rapid propulsion through the air. This, of course, is essentially necessary in signals, as it is most important that each star discharged should burn so as to insure of there being no interruption in the continuity of the system. Therefore in forming the stars, in addition to the lateral channels d d, which serve to ignite the powder in the chamber below, I form or mold the star with a small socket-chamber, d', as it were, at its center, and which extends from its upper surface down through the body of the composition to a depth, say of a quarter or half inch, and which leaves the base of the star solid and firm to resist the shock of the powder. In the chamber d' of each star is inserted a piece of common quick-match, y, previously dipped in a solution of gum and mealed powder. The gum causes the section of the match y, which is inserted into the chamber d' to adhere to its bottom in a man-

ner to insure its retention in the chamber, while the upper surface of the match should project, say about a quarter of an inch, as shown in Fig. 5, and the quick-match *y* being ignited by the time-fuse, and burning down in the chamber *d*, so ignites the star within its interior center as to render it impossible to fail to burn, or being once ignited to be blown out.

Now, the arrangement of grooves or channels of ignition *d d*, in connection with the form and arrangement of the powder-chambers into which they lead, constitutes the most important elements of my invention, as will presently be explained. *c*, *c¹*, and *c²* are the powder-chambers, and may be angular, as shown at *c²*, curved, as shown at *c¹*, or semi-oval, as shown at *c*, or of any other form that possesses, for my purpose in use, the advantages that are secured through the employment of either of the forms mentioned.

Now, it will be seen that the lateral ignition-channels of the star lead into the powder-chamber at the point or points where there is the least quantity of powder, and owing to the form of the chamber the full force of the powder is concentrated directly under the center of the star, thus requiring a very little powder to be used to insure the desired projecting of the star in a manner, and to an altitude, that insures the results aimed at being attained in the most satisfactory manner, and which at the same time, owing to the smallness of the quantity of powder used, precludes all danger of explosion of the case or recoil; and the star not having a central channel extending through the same, no vent is provided through which any of the intense force of the powder might escape and be lost. These powder-chambers *C*, *C¹*, and *C²* are provided with thin walls or film-caps *a a*, constructed of felt, rubber, or any other like suitable material, fibrous or elastic, and are provided with central openings or apertures *b b*, as clearly shown in Fig. 2, which wall *a* prevents the force of the powder-charge from driving the fire through the time-fuse in a manner that would cause its being consumed too rapidly, while at the same time the central opening *b* provides a means that insures of its proper ignition. The dimensions of the case *A* are to be such as to leave above the upper fuse *C³* a chamber, *E*, which is to contain powder for the ignition of the signal; and the wall of which chamber serves as a barrel, as it were, to give direction to the colored stars as projected. In a suitable opening cut through the wall of the case *A*, and leading into the chamber *E*, is screwed a percussion-tube or cap-nipple, *F*. The chamber *E* may be filled or only partially filled, as shown in Fig. 2, with powder *E¹*. Any quantity of powder that is sufficient, through its explosion, to throw off the cap or top covering with which the case is provided, and to ignite the fuse below, is all that is desired. The composition that forms the time-fuse, its wall, the powder, and the

colored stars, are all secured in the case *A* in the usual manner. The tool or instrument with which the tamping of the time-fuse composition is effected should have its head turned, or be of the form which corresponds with that which it is deemed desirable to give to the powder-chambers *C C¹ C²*. After these chambers are formed, with the same tool or instrument the felt, rubber, or other material which is to form the wall *a* of the respective chambers, is readily forced in proper position. The case being properly filled, and an air-tight covering or cap being provided for its upper section, and a suitable air-tight cap or shield, *F'*, being provided for the percussion tube or nipple *F*, the entire surface of the case may be coated with a solution of shellac or other water proof composition, and which will protect the interior from all moisture, air, or other injurious action of the atmosphere.

Now, a signal has more particularly been described which contains three stars; but, of course, whether it contains only one, or two, or even more than three, the same general principle will be observed in its construction. To fire the signal, the cap *F'* has simply to be torn off, and a percussion-cap is placed on the nipple *F*, which cap may be exploded by striking the same against the side of a vessel, or other inert body, or, if desired, the cap may be exploded by a hammer or other device, which, not being part of my invention, is not shown on the drawing, but which the most ordinary mechanical skill, if desired, could tell how to apply. The firing of the cap, of course, ignites the powder in the chamber *E*, the explosion of which throws off the cap from the mouth of the case and ignites the time-fuse *C³*, which fires the quick-match *y*, which ignites the star and the time-fuse *C³* also through the channels *d d*, which for the purpose may, if desired, be provided with a L-shaped quick-match, *xx*, as shown in Fig. 5, ignites the powder in the chamber *c²*, and which, exploding, projects the star *D*, and at the same time, through the opening *b* in the wall *a*, ignites the time-fuse *C²*, and which is designed to burn a sufficient interval to allow the first star to ascend to its full altitude and burn out or become extinguished before firing the powder in the next consecutive chamber, and so on until the stars are all exhausted.

What I claim as new, and desire to secure by Letters Patent of the United States, is—

1. The colored star or stars *D D* for pyrotechnic night signals, constructed with one or more vertical lateral grooves or channels, *d d*, as and for the purpose specified.

2. The colored stars *D D*, having channels for igniting the powder in the chamber below, and a central chamber, *d*, for igniting the interior surface of the star, substantially as and for the purpose specified.

3. A time-fuse, having a powder-chamber of substantially the form shown, the same being protected by a thin wall or film, *a*, of

some suitable flexible material, and having an opening or aperture, *b*, as and for the purpose specified.

4. The combination of one or more colored stars, *D D*, time-fuses *C C¹ C²*, having powder-chambers, and a wall or film, *a*, with a central opening, *b*, substantially as and for the purpose specified.

5. A pyrotechnic night-signal, consisting of a case, *A*, having its lower section plugged by a composition of some suitable non-combustible material, and its upper section protected by a water-proof cap or covering, one or more colored stars, *D D*, and one or more time-fuses,

the latter being formed with a counter-sunk powder-chamber, and a powder-chamber, *E*, and a nipple or percussion-tube, *F*, the whole combined and arranged to operate in connection with any public or private system or code of signals, substantially as and for the purpose set forth.

In testimony whereof I have hereunto signed my name to this specification in the presence of two subscribing witnesses.

EDWARD F. LINTON.
